UNITED STATES PATENT OFFICE

120,646

DESIGN FOR A TOY ANIMAL

Anna W. Lowin, Chicago, Ill.

Application March 18, 1940, Serial No. 91,020

Term of patent 14 years

To all whom it may concern:

Be it known that I, Anna W. Lowin, a citizen of the United States, residing at Chicago, in the county of Cook and State of Illinois, have invented a new, original and ornamental Design for a Toy Animal, of which the following is a specification, reference being had to the accompanying drawing, forming part thereof.

In the drawing:

Fig. 1 is a front view of a toy animal showing my new design;

Fig. 2 is a side view thereof, and,

Fig. 3 is a rear view thereof.

I claim:

The ornamental design for a toy animal, as shown.

ANNA W. LOWIN.
